KERF-CUTTING MACHINE

Laurence E. Topham, Wenham, and Garrett P. S. Cross, Beverly, Mass., assignors to United Shoe Machinery Corporation, Flemington, N. J., a corporation of New Jersey

Original application February 14, 1945, Serial No. 577,750. Divided and this application July 13, 1948, Serial No. 38,514

4 Claims. (Cl. 144—2)

1

This invention is related to the art of making individual foreparts and heel parts of jointed lasts of the type described in our U. S. application Serial No. 577,750, filed February 14, 1945 (now Patent No. 2,535,465, granted December 26, 1950). The present application is a division of our former application identified above.

The whole problem envisaged by the invention includes boring a master hole widthwise through a rough block, generating a joint surface on one end of the block, cutting a heightwise kerf in the joint end of the block, establishing a turning axis in a certain precise relation to the joint surface, the master hole and the heightwise kerf, and thereafter utilizing the joint surface to locate the block in a desired relation to a copying lathe and to rotate the block about its turning axis.

The present application is concerned more especially with means for cutting the heightwise kerf in the joint end of a block and with means for locating the kerf in a precise relation to the master hole, the joint surface, and what will eventually be the turning axis of the block, since the kerf is destined to play a part in locating the block widthwise in the copying lathe.

The primary purpose of the kerf above mentioned is to accommodate a link by which a forepart and a heel part may be connected with each other. In some lasts the configuration of the kerf must provide one or more minor recesses in which an element of hardware may have clearance for movement. Therefore, the apparatus hereinafter described and claimed includes novel features and improvements by which an operator may control a kerf-cutter selectively according to various predetermined requirements and thereby cause it to cut kerfs of various configurations each of predetermined length and configuration.

Referring to the drawings,

Fig. 1 represents a top plan view of an apparatus designed and equipped to prepare forepart blocks for subsequent turning in a copying lathe;

Fig. 2 is an elevation of the kerf-cutter as viewed from a plane indicated by line II—II in Fig. 1;

Fig. 3 represents a forepart block after it has been prepared by the apparatus represented in Fig. 1, the kerf therein having simple configuration and no supplemental recess or heightwise extension;

Fig. 4 represents an end elevation of the joint end of the block represented in Fig. 3;

Fig. 5 represents a side elevation, partly in section, of the joint portion of a forepart block in

2

which a kerf has been extended heightwise above and below its primary limits;

Fig. 6 is a top plan view of mechanism for locking the cradle by which the kerf-cutter is carried, the carriage by which the cradle is carried, and the carriage by which the work is carried to and from the station where the kerf-cutter operates;

Fig. 7 is a sectional elevation of structure included in Fig. 2 but viewed from the opposite side;

Fig. 7a is a sectional elevation of a control included in Fig. 7 and occupying the same position as in the latter;

Fig. 8 is a sectional elevation of a trip mechanism represented in another relation in Fig. 7;

Fig. 9 represents the structure of Fig. 7 as when the kerf-cutter is fully advanced (to the left) and cutting the deepest part of a kerf;

Fig. 10 represents the same structure as when the kerf-cutter is retracted to an intermediate position and latched; and

Figs. 9a and 10a are sectional elevations of a control in different positions corresponding to Figs. 9 and 10, respectively, it being the control otherwise represented in Fig. 7a.

Typical examples of kerf-cutting with the apparatus hereinafter described are illustrated in Figs. 3, 4, and 5, in which a rough-hewn forepart block 11 is provided with a master hole 12 and a joint surface including a semi-cylindrical hinge surface 13 and a stop shoulder 14 below it. The hole 12 extends widthwise through the block and is open at both ends. Its primary purpose is to provide bearings for an anchoring pin (not shown) by which a link may be used to couple the forepart and a heel part of a hinge last in the manner illustrated in U. S. Letters Patent No. 2,094,118, granted September 28, 1937.

The kerf 15 extends heightwise of the block 11 and intersects the hinge surface and the hole 12 to provide a space in which a portion of a coupling link may be installed. A broken line 16 (Fig. 3) indicates the approximate location of a saw-cut by which some of the surplus wood of the block will be severed, and the broken lines 17 indicate the shape of a forepart to be generated in a copying lathe. A kerf of the shape and proportions represented in Fig. 3 may suffice

for some coupling links, but the hardware with which some lasts are equipped may require the kerfs to be further extended above the hinge surface or below it, or both above and below it, as represented in Fig. 5.

The organization represented in top plan view

in Fig. 1 includes a flat horizontal bed 20 constituting a stationary support, a rotary power-driven shaft 21 (vertical axis) journaled therein, a formed cutter 22 affixed to the shaft and located above the bed, parallel rails 23 and 24 affixed to the bed, a work-carriage 25 guided along a straight path by the rails, work-holding means mounted on the carriage 25, a stop 26 for arresting the carriage 25 at an operating station where it will hold a rough work-block 11 at station B in the path of a power-operated kerf-cutter 27, a motor 28 for driving the kerf-cutter, a cradle 29 on which the cutter 27 and motor 28 are mounted, a cutter-carriage 30, and other elements herein-after described.

The work-carriage 25 stands at its loading position in Fig. 1 where it will hold a work-block at station A. The work-holding means includes a pair of aligned trunnions 31, 32, a clamping bar 33 and other elements by which a block may be clamped heightwise while the trunnions 31, 32 occupy the hole 12 in the block. The trunnion 32 is carried toward and from the trunnion 31 by a clamping member 34 to which clamping movement may be imparted by a lever 35 and a connecting link 36.

The axis of the trunnions 31, 32 is parallel with the straight path of the carriage 25 along which a work-block is transferred from station A to station B. The block is thus carried widthwise past the formed cutter 22 by which a joint surface is generated thereon (Figs. 3, 4 and 5). An adjustable screw 37 carried by the carriage 25 is arranged to cooperate with the stop 26 to arrest the carriage when the block arrives at station B.

To provide for locking the work-carriage at its operating station, a toothed locking bar 38 is affixed to the carriage, and cooperative locking pawls 39 and 40 (Fig. 6) are installed in a fixture 41 fastened to the bed 20. The pawls are connected to the fixture by pivot pins 42 and are initially retracted from the path of the bar 38 by a ram 43. Spring followers 44 are arranged to shift the pawls to their locking positions when the ram 43 is retracted by a compression spring 45. The ram 43 is connected to an operating arm 46 loosely mounted on a rockshaft 47. One purpose of the rockshaft is to feed the kerf-cutter toward the work and retract it therefrom, but it also operates the arm 46 with which it has a lost-motion connection. For the latter purpose a collar 50 affixed to the rockshaft is provided with a lug 49 that initially restrains the arm 46 by engaging a shoulder 48 thereof (Figs. 6 and 7). As the kerf-cutter advances, the lug 49 recedes from the shoulder 48 after the work-carriage 25 has been locked at the operating station corresponding to station B of a work-block.

The cutter-carriage 30 is constrained to an inclined path at extending right-angles to that of the work-carriage 25 by a frame 51 fastened to the bed 20, one of its margins (Fig. 1) being arranged in a guiding groove in the frame and its opposite margin being provided with a straight bar 52 arranged in bearings in the frame and adapted to slide therein (Figs. 2, 7 and 10). The bar 52 is provided with gear teeth 53 forming a rack, and these are meshed with a pinion 54 affixed to the shaft 47. A hand-lever 55 (Figs. 1, 2 and 7) fastened to this shaft enables an operator to move the cutter-carriage along its inclined path toward and from the work-carriage. A kerf of the form represented in Fig. 3 may be produced without rocking the cradle 29 on the trunnions 56 by which it is

mounted on the carriage 30. An adjustable stop 57 is provided to arrest downgrade travel of the carriage 30 according to the desired depth of the kerf to be cut.

When the cutter-carriage is retracted to its initial position (Figs. 1, 2 and 7) it is automatically latched by a shoulder 60 of a latching arm 61. The arm is connected to the frame 51 by a pivot pin 62, and is biased by a spring 63 that normally holds it against a latching block 64 fastened to the carriage. The cutter-carriage is thus initially restrained from sliding downgrade, but it may be released from the latching arm in consequence of being retracted slightly 10 upgrade as represented in Fig. 8. Such retraction causes the block 64 to engage a camming surface 65 of the arm and to deflect the latter far enough to remove the shoulder 60 from the path of the block, also far enough to place the tip of the arm 61 under a retaining shoulder 66 of a trigger 67. The latter is connected to the frame 51 by a pivot pin 68 and is biased toward the arm 61 by the spring 63. Once the arm 61 has been placed under restraint of the trigger 67 the operator may use the hand-lever 55 to retard the travel of the carriage 30 toward the work and thereafter to accelerate penetration of the work by the kerf-cutter which, as illustrated in Fig. 2, is a well-known type of 20 chain-saw.

Before the cutter-carriage is arrested by the stop 57, the latching block 64 will strike the trigger 67 (Fig. 9) and displace it to trip the latching arm 61. The downgrade traverse of the 30 cutter-carriage will produce a kerf 15 of the configuration represented in Fig. 3, and if no elongation of the kerf is needed the operator will retract this carriage, without interruption, to its initial position by moving the hand-lever 40 55 reversely to the position represented in Fig. 7.

As the rockshaft 47 (Fig. 7) turns counterclockwise to advance the cutter 27 toward the work, it first permits the pawls 39 and 40 (Fig. 6) to lock the work-carriage 25, and thereafter permits the arm 46 to remain still while the lug 49 recedes from the shoulder 48 (Fig. 9).

If, after feeding the cutter 27 into a block 11 to cut a kerf 15 of the desired depth, the operator wishes to elongate the kerf above or below its initial limits (Fig. 5) he may do so 50 by rocking the cradle 29 on its trunnions 56. It may be desirable to withdraw the cutter part away from the kerf before rocking the cradle, the chief consideration on this score being the requirements of the hardware to be installed in the last. As herein represented, the latching arm 61 is provided with a latching shoulder 70 with which the block 64 will cooperate to latch the carriage 30 (Fig. 10) at an intermediate 60 station in its path of travel, where it will be restrained from sliding downgrade while the cutter projects some distance into the kerf.

The mechanism for rocking the cradle 29 includes (Fig. 1) a hand-wheel 71, a shaft 72, a disk 65 73 (Figs. 6 and 7) carried by the shaft, a crankpin 74 carried by the disk, a lever 75, a link 76 connecting the crankpin and the lever, a rod 77 affixed to the cradle, and a sleeve 78 connecting the lever and the rod 77. A fulcrum-pin 79 supports the lever 75, and a pivot-pin 80 connects the lever and the sleeve 78. A locking bolt 81, biased by a compression spring 82, is normally pressed against the surfaces forming a V-shaped 70 notch 83 in the disk it thereby maintains the lever 75

75 at an intermediate position in which the rod 77 is parallel with the path of the carriage 30. The rod 77 may then slide through the sleeve 78 without rocking the cradle 29.

The bolt 81 is effective also to lock the cutter-carriage 30 in consequence of being thrust into a socket 84 in a sleeve 85. This sleeve is fastened to the shaft 47 and is so placed that the socket will be in register with the bolt (Fig. 10a) only when the cutter-carriage is at the position corresponding to the location of the latching shoulder 70 (Fig. 10). Then, if the hand-wheel 71 be rotated, one surface or the other of the V-notch 83 will act on the bolt with the effect of a cam and thereby shoot the bolt into the socket 84. The cutter-carriage will thus be locked and will remain locked until the cradle is returned to its median or initial position. One complete revolution of the hand-wheel will elongate the kerf as represented in Fig. 5 and finally permit the spring 82 to retract the bolt from the socket 84. The operator may then retract the cutter-carriage to its initial position (Fig. 7) where the latching shoulder 60 will again take control. During this final stage of retraction the shaft 47, turning clockwise (Fig. 10), will carry the lug 49 to the shoulder 48 and thereafter cause the ram 43 to retract the locking pawls 39, 40. It will also carry the socket 84 (Fig. 7a) out of register with the bolt 81 and cause the sleeve 85 to lock the train of mechanism by which the cradle 29 is actuated. The two trains of mechanism for feeding the cutter-carriage and the cradle, respectively, are arranged to be locked alternatively by the bolt 81 only when each occupies a predetermined position, and each, in turn, governs the locking effect of the bolt on the other.

Having thus described the invention, what we claim as new and desire to secure by Letters Patent of the United States is:

1. An apparatus for operating on a last-part block, the apparatus comprising means for holding such a block, a cutter-carriage, a support on which said carriage and the holding means are movably mounted, means for moving the carriage toward and from a work station, a cradle movably mounted on the carriage, a planar kerf-cutter mounted on the cradle, actuating means engageable with the cradle for moving the cutter in translation in its plane and toward or from the carriage to elongate a kerf in which the cutter is situated, and locking means mounted on said support including a member interposed between and engageable with one or the other of the respective means for moving the carriage and the cradle to lock them alternatively and to unlock each of them when locking the other.

2. An apparatus for operating on a last-part block, the apparatus comprising a frame, means on said frame for holding such a block, a carriage, a kerf-cutter on said carriage for movement therewith toward and from the block holding means, means on said frame by which said carriage is guided, a spring-biased latching member mounted on the frame and engageable with the

carriage to prevent advancing the latter from a primary retracted position, and a spring-biased trigger mounted on the frame and engageable with said latching member to catch the latter in a retracted position, the carriage and said latching member having cooperative camming surfaces by which the latching member is retracted from its latching position and placed under restraint of said trigger in consequence of retracting the carriage beyond said primary retracted position, the trigger being movable from biased position by the carriage to trip the latching member as the carriage advances from said primary retracted position.

15 3. An apparatus for operating on a last-part block, the apparatus comprising a frame, means mounted on the frame for holding such a block, a carriage, a kerf-cutter on said carriage for movement therewith toward and from the block holding means, means on the frame by which said carriage is guided, a spring-biased latching member connected to the frame and engageable with the carriage to prevent advancing the latter from a retracted position, and spring-biased 20 means mounted on the frame and engageable with the latching member when the latter is in an inoperative position and thereafter, when the carriage is advanced, displaceable by the latter to trip the latching member.

25 4. An apparatus for operating on a last-part block, the apparatus comprising a frame, a work-carriage provided with means for holding such a block, a cutter-carriage provided with a cutter for cutting a kerf in a block so held, means mounted 30 on the frame for guiding said work-carriage to and from an operating station, means mounted on the frame for guiding said cutter-carriage toward and from said station, a manually movable member mounted on the frame, and two 35 means mounted on the frame each having operative connection with said member, one movable into the path of the work-carriage for engageably locking said work-carriage at said station and the other being operatively connected to 40 said carriage and actuatable by the member for 45 moving said cutter-carriage.
